DEVICE FOR THE INTRODUCTION, IMMERSION, AND ASPERSION OF MEDICAMENTS

Filed March 29, 1929

BY

Emilio BUCHWALD ^{INVENTOR}
George C. Heinrich,
ATTORNEY

UNITED STATES PATENT OFFICE

EMILIO BUCHWALD, OF BUENOS AIRES, ARGENTINA

DEVICE FOR THE INTRODUCTION, IMMERSION, AND ASPERSION OF MEDICAMENTS

Application filed March 29, 1929. Serial No. 350,880.

The present invention refers to a new device for clinical use for the introduction, immersion and aspersion of medicaments in the form of powder, pomade, liquid, etc., in any 5 internal part of the body, the employment of which represents distinct advantages of a practical order, inasmuch as its low cost and simplicity makes it an instrument within the reach of everybody, apart from which it is 10 of positive results.

In order that my application may be more comprehensible, I have illustrated same with various figures, wherein:

Fig. 1 is a longitudinal sectional view of 15 the device.

Fig. 2 is a longitudinal sectional view of a variation of same.

Fig. 3 is a view of one of the rods, forming 20 a complement of the device.

Construction

The construction comprises a depository with walls of glass (a) and bases of metal (b), into which is introduced the medicinal 25 substance, either in the form of powder, pomade, liquid, or any other. In its lower part is found a nozzle (c) to which is attached the end of a rubber tube (d) pertaining to a bulb of the same material. In this 30 drum or deposit (a) (b), is inserted a canula (e), which may be straight, partially or totally curved, and its end may be acute, obtuse, or infundibuliform, according to the nature and object; said canula may have or not the 35 division (f) which divides it in two (Fig. 1), or it may be simple as shown in Fig. 2, the diameter and length varying according to circumstances, and moreover, the canulas 40 may have holes (i) in their sides, in order that the introduction of the medicament may not only be effected by the end of same, but also laterally.

The canulas (e) and (e') and any other 45 which may be manufactured, are always part and complement of the drum (a) (b), which may be constructed in accordance with Fig. 1, that is, following the line of the canula (e), or forming a right angle with same, or in any 50 other convenient manner.

The canula (e'), Fig. 2, free of internal

division, has as a propellant of the medicament, a spiral (g), thread, spring, or rod, which pushes or works in such a manner, that it effects the introduction of the medicament.

As will be seen, the various canulas (e) 55 (e'), which may be conceived, are interchangeable, and that which is considered the most convenient may be placed in the drum (a) (b).

The rods (j) (k), Fig. 3, are complements 60 of the device, the object of which will be explained, and may be of rigid or flexible material, of one sole piece (k) or divided (j), or adopt the most convenient form. The diameter and length of said rods may vary 65 according to the special cases in which they are employed.

Working

The device works as follows:

On the canula (e) (e') being introduced it is necessary to avoid that the pus or liquid matter of the body, by automatic effect, may ascend by the canula and obstruct or embarrass its working, and for this object I 75 insert in the interior of the canula (e) (e'), the rod most adapted, be such (j) or (k), rigid or flexible according to the case. The same is later withdrawn, to then effect the introduction of the medicament. If it is desired to use the canula (e), the bulb (d) will be employed in order that the medicament in the form of powder which is generally 80 found in the drum (a) (b) may be pushed in a forward direction, being introduced by the aperture (h) and deposited in the part of the body which has been reached by the canula. The air which has served to draw the medicament does not remain, nor is it lodged, 85 as happens with the usual apparatus, but returns by the other higher half of the canula (e), Fig. 1, wherein the arrows indicate the passage of air, the latter being obturated in the lower part by the wedge (l), which is removable.

When it is not desired to employ air as the propellant, the thread or spiral (g) will be used, (Fig. 2), which in turn may be varied as to form, and it may take that of a simple rod, spring, piston, etc., without this repre-

senting a departure from the sphere of the invention, the principal features of which are the method of propulsion with the deposit of the medicament, and the interchangeability of the various canulas.

Having thus described my invention, what I claim as new and desire to secure by Letters Patent is:

1. In a device as described, a glass depository for the reception of a medicament, perforated metal caps for said depository, a tube passing through the perforations of said caps and said depository, said tube having a plurality of openings formed in its wall and an aperture within said depository, a longitudinally extending partition dividing said tube, and a means for expelling the medicament contained in said depository into a body.
2. In a device as described, a glass drum for the reception of the medicament, metal caps closing the ends of said drum and having central openings, a perforated tube extending through the openings in said caps and the drum, having a feed opening within said drum, a longitudinally extending partition in said tube, a nozzle formed with one of said caps adapted for engagement by a rubber tube, and a bulb at the end of said rubber tube for expelling the medicament in said drum into the cavities of a body, and means for closing one end of said perforated tube, said tube adapted for the reception of means preventing its obstruction.

In testimony whereof, I affix my signature.

EMILIO BUCHWALD.
